UNITED STATES PATENT OFFICE.

SIDNEY S. CAMERON, OF ST. PAUL, MINNESOTA.

TOE-FORMING MACHINE.

1,114,445.

Specification of Letters Patent. Patented Oct. 20, 1914.

Application filed October 4, 1913. Serial No. 793,398.

To all whom it may concern:

Be it known that I, SIDNEY S. CAMERON, a citizen of the United States, residing at St. Paul, in the county of Ramsey and State 5 of Minnesota, have invented a new and useful Improvement in Toe-Forming Machines, of which the following is a specification.

An object of this invention is the production of a machine for rolling out and smoothing leather in finished condition on the toes of shoes during the process of manufacture after the shoes have been lasted and prior to inseaming. Primarily 15 said invention is applicable to shoes of that class generally known as Goodyear welt.

Previous to my invention, it has been customary to smooth out the wrinkles by pounding or rubbing the leather on the last 20 by hand, whereas by the use of my invention the leather is smoothed evenly and quickly by machine rolling with less hand labor and expense than heretofore, and with improved results. This rolling operation 25 occurs previous to the inseaming or welting operation, and is designed to prevent what is known in the art as grinning of the seam around the toe. The machine is also useful for rolling and removing wrinkles from 30 the counter toward the heel seat and when made of proper dimensions and slightly modified can be used for rolling out leather or other materials of any form.

In the accompanying drawings forming 35 part of this specification, Figure 1 is a side elevation of my invention partly in section, and broken away to expose part of the mechanism to full view; Fig. 2 is an end elevation partly broken away and in section, and Fig. 3 is a plan of two of the rollers employed in the machine.

A indicates a shaft suitably journaled upon a base B and carrying tight and loose pulleys 2 and 3, by one of which the shaft 45 is actuated. The end of the shaft opposite that on which the pulleys are mounted projects from journal boxes 4 and 5 formed integral with the base and carries a spool 6, the body of which is secured to the shaft 50 by a key 6', (see Fig. 2). The opposite ends 7 and 8 of this spool are respectively fastened by screws 9 to circular roller sup-

porting plates 10 and 11, which are adapted to revolve concentrically with the spool and shaft. These circular plates 10 and 11 have 55 freely journaled therein a plurality of rollers 12, each roller being arranged parallel to the axis of the shaft and all of said rollers being arranged in series side by side in a circle around the shaft. Thus all of 60 the rollers are revolved together with the shaft, but each roller is free to revolve independently in the end plates 10 and 11, on its own independent axis. The ends of 65 the rollers are formed with gudgeons 13 and 14, which are suitably journaled in bearing cups 15 formed in the end plates 10 and 11. The central portion of each of the end plates 10 and 11 is formed with an opening 16 and an inwardly projecting 70 guard flange 17. The flanges 17 on the end plates assist in forming oil channels to lubricate the roller bearings by centrifugal force when the device is revolving and said opening 16 in end plate 10 allows access to 75 the oil openings 18 leading into bearings 15 for lubricating purposes.

The journal box 4 is formed on its end with a radial plate 19, the periphery of which is concentric with the axis of the 80 shaft A and to said periphery an internal gear 20 is secured, said gear being formed with a shoulder 21 spaced from said plate 19 and with a collar 22, the latter being fastened to said periphery by screws 23. 85 The space bounded by the shoulder 21, the inner face of the radial plate 19 and the inner surface of collar 22 forms a circular channel in which the roller supporting plate 11 is freely journaled so that the latter may 90 be revolved by the shaft A with little friction and with little or no lubrication. The teeth of the internal gear 20 face inwardly and are of sufficient length to engage the teeth of two rows of pinions 24 and 25 95 which are shrunk or otherwise secured to the gudgeons 14 on the ends of the rubbing rollers 12. The pinions 24 are alternately positioned lengthwise upon the gudgeons 14, in other words the pinion on each succeeding rubbing roller is placed in line to assume a position in one or the other of the series of pinions, so that pinions of greater outside diameter than that of each rub-

bing roller may be employed to mesh with the teeth of the internal gear. The group of shaping or rubbing rollers and their supports produce a spindle and each time this 5 spindle revolves, every rubbing roller has imparted to it a plurality of revolutions by the pinions meshing with the teeth of said stationary internal gear. Each shaping or rubbing roller thus revolves independently 10 upon its own axis at the same surface speed as the periphery of the spindle while all of the shaping rubbing rollers of the spindle are revolved together co-axially with the shaft A. The diameters of the rollers correspond and the pitch diameter of each 15 pinion is the same as the diameter of each roller. There is therefore only a rolling contact between the peripheries of the rollers and the material being formed which is 20 an advantage, a rubbing contact being highly objectionable because it causes burning, bruising and uneven stretching of the material. Oil or other lubrication may be applied to the internal gear by the oil cup 25 26. The inner edges facing each other of the end plate 10 and the internal gear 20 are formed with inwardly projecting in-turned guards 21 and 22, the faces of which are curved to prevent abrasion of the 30 surface of the shoe by contact therewith.

At one side of the device in suitable position to support the toe of the shoe, so that its surface may be rolled by the peripheries of the rollers is a suitable rest C of any 35 convenient form, that illustrated being of ordinary construction. This rest has a circular plate rest 26, the surface of which is knurled and adapted to receive and hold the lower portion of the toe of the shoe. This plate is 40 journaled upon a screw 27, and is carried by a horizontally journaled support 28 in a yoke 29 formed on the upper end of the arm 30. A spring 31 holds the support 28 with its rest plate 26 in forwardly inclined position normally against the stop 31. The 45 lower end of the arm 30 is mounted upon and secured to a shaft 32, which is journaled upon the bracket 33 formed on the base of the machine. A collar 34 is secured rigidly 50 to the shaft 32 and has secured to its periphery a draw spring 35, which is anchored to an arm 36 extending backwardly from the bracket 33. This spring yieldingly holds the arm 30 in upright position against the stop shoulder 37. In this manner the toe of the 55 shoe may be placed on the rest plate 26, and moved backwardly and tilted at any angle required so that the surface of the toe may be applied against the revolving rollers 12 60 and the wrinkles in the latter quickly and effectively smoothed out, producing finished work. The rollers being positively driven while the spindle is revolved serves to gradually and quickly draw and form the leather

on a regular curve without abrading or 65 wrinkling the material.

In accordance with the patent statutes, I have described the principles of operation of my invention together with the apparatus which I now consider to represent the best 70 embodiment thereof, but I desire to have it understood that the construction shown is only illustrative and that the invention can be carried out by other means and applied to uses other than those above set forth within 75 the scope of the following claims.

Having described my invention, what I claim as new and desire to protect by Letters Patent is:—

1. A toe forming machine, consisting of 80 a revoluble spindle having a plurality of shaping rollers journaled freely therein, said rollers being arranged longitudinally parallel with the axis of said spindle and in a circle co-axial therewith, and means to produce revolution of each of said rollers in its journal interdependent with the revolution of said spindle.

2. A toe forming machine, comprising, in combination, a drive shaft, a spindle mounted upon said shaft and adapted to revolve therewith, and a stationary internal gear co-axial with said shaft, said spindle having a plurality of rollers longitudinally parallel with and arranged in a cluster co-axially 95 about said shaft, said rollers having drive pinions, the teeth of which mesh with the teeth of said internal gear, whereby as said spindle is revolved, said rollers turn with said spindle and have imparted to them a 100 surface speed producing rolling contact against the material being formed.

3. A machine for smoothing leather, comprising in combination, a main revoluble element, a plurality of subordinate elements carried by said main element, and means for imparting motion to said subordinate elements, whereby they have motion interdependent with the motion of said main element and friction upon the material being smoothed is reduced.

4. In a machine for smoothing leather, a main revoluble element, a plurality of rubbing rollers journaled freely and arranged in circumferential alinement and co-axial 115 with said revoluble element, an internal gear about said series of rollers, and a pinion carried by each of said rollers with its teeth meshing with the teeth of said internal gear, whereby as said main revoluble element revolves, each of said rollers is revolved upon its own axis, and all of said rollers are moved around the axis of said main revoluble element.

5. A machine for smoothing leather, comprising, in combination, a main revoluble element, a plurality of rollers carried by said main element having drive pinions, and a

stationary gear with the teeth of which the teeth of said pinion mesh to cause them to revolve, the pitch diameter of each of said pinions being the same diameter as that of the roller on which it is mounted, whereby a rolling contact is produced without rubbing between said rollers and the material being formed.

In testimony whereof, I have signed my name to this specification, in the presence of 10 two subscribing witnesses.

SIDNEY S. CAMERON.
